UNITED STATES PATENT OFFICE.

NELSON M. SHEPARD, OF BROOKLYN, NEW YORK.

DESIGN FOR AN ORNAMENTAL CHAIN.

Specification forming part of Design No. **11,157**, dated April 15, 1879; application filed January 29, 1879.
[Term of patent 7 years.]

To all whom it may concern:

Be it known that I, NELSON M. SHEPARD, of Brooklyn, in the county of Kings and State of New York, have invented, originated, and designed a Chain; and I do hereby declare that the following, taken in connection with the drawings which accompany and form part of this specification, is a description of my invention sufficient to enable those skilled in the art to practice it.

The nature of my design is fully represented in the accompanying drawing, to which reference is made.

Heretofore watch, vest, or neck chains have been designed of a great variety of patterns, producing articles of manufacture both ornamental and useful, but, by reason of the prevailing customs, soon become unmarketable, and others of a different shape and formation are desired.

The object of my design is to more particularly furnish a chain that will better meet the requirements of a certain large class of people who desire to have chains for use and ornament illustrative of their profession, as well as to supply the almost never-ceasing demand of the many for new, odd, and useful articles for ornamentation and use and for other purposes.

The design consists of a chain for vest or neck wear composed of various parts, representing a gun, shells, glass balls, shot, cartridges, links, and a swivel or clasp.

A is a bar, made in the shape of a breech-loading gun, in position to receive the shell or cartridge. B¹ B² B³ B⁴ B⁵ B⁶ are links which connect the bar or gun A to the shell C¹.

E¹ is an eye or link fastened to the gun A. E² is an eye fastened to the shell C¹. B⁷ B⁸ B⁹ B¹⁰ are also links. B⁷ is fastened to either of the links B¹ B² B³ B⁴ B⁵ B⁶, and B¹⁰ to the eye E³, fixed to the shell C².

B¹¹ B¹² B¹³ B¹⁴ B¹⁵ B¹⁶ B¹⁷ B¹⁸ are links that connect the shells C¹ C³ C⁴ C⁵ C⁶ and the glass balls F¹ F² F³ F⁴ together, by being linked through the eyes E⁴ E⁵ E⁶ E⁷ E⁸ E⁹ E¹⁰ E¹¹ E¹² E¹³ E¹⁴ E¹⁵ E¹⁶ E¹⁷ E¹⁸ E¹⁹. E²⁰ is an eye in shell C⁶. E²¹ is an eye in shot G¹.

Shell C⁶ is connected to shot G¹ by the link B¹⁹. E²² is an eye in shot G¹, through which the link B²⁰ passes, connecting the shot G¹ to the eye E²³, fastened to the cartridge H¹.

Link B²¹ connects cartridge H¹ to shot G² by passing through the eye E²⁴, fastened to the cartridge H¹, and through the eye E²⁵, fastened to the shot G². Link B²² connects shot G² to cartridge H² by passing through eye E²⁶, fastened to shot G², and eye E²⁷, fastened to cartridge H². Link B²³ connects cartridge H² to shot G³ by passing through eye E²⁸, fastened to cartridge H², and eye E²⁹, fastened to shot G³.

E³⁰ is an eye fastened to shot G³, through which the link B²⁴ passes, and link B²⁵, connecting link B²⁵ to link B²⁶, and B²⁶ to B²⁷, and B²⁷ to B²⁸, and B²⁸ to B²⁹, and B²⁹ to ring K in swivel or catch M.

Any number of links, shells, glass balls, cartridges, and clusters of shot, and any number of shot in a cluster, may be varied, to accommodate the size, weight, and length of chain desired; or the chain may be made up of gun, shells, glass balls, links, and swivel or catch, or may be made up of gun, cartridges, shells, links, and swivel or catch.

In place of C², a cartridge or a glass ball may be used. Any kind of a swivel or catch may be used in place of the one illustrated.

The glass balls are intended to represent those used by sportsmen at shooting-matches.

The links may be of any form, and any of the parts illustrated and explained, that constitute the whole, may be of any size or weight, and made of any suitable material, cast or molded, struck up, each part solid or hollow, or partially hollow, or formed of pieces and soldered or brazed together, or made in any other manner.

I claim—

1. The design for an ornamental chain, consisting in the representation of the gun A, shell or shells C¹, glass ball or balls F, shot G, cartridge or cartridges H, link or links B, and swivel or catch M, substantially as described, and shown in the accompanying drawing.

2. The design for an ornamental chain, consisting in the representation of the gun A, shell or shells C¹, glass ball or balls F, link or links B, and swivel or catch M, substantially as described, and shown in the accompanying drawing.

3. The design for an ornamental chain, consisting in the representation of the gun A,

the shell or shells C¹, cartridge or cartridges H, link or links B, and swivel or catch M, substantially as described, and shown in the accompanying drawing.

NELSON M. SHEPARD.
